DEVELOPING REEL

Albert Del Pozo, Jr., and Michael W. Mettenleiter,
New York, N. Y.

Application March 28, 1947, Serial No. 737,870

7 Claims. (Cl. 242—77)

1

The present invention relates to apparatus for processing and in particular, developing photographic film and the like.

It is an object of the present invention to provide an improved device for processing and in particular, developing photographic film which yields a substantially perfect uniformity of distribution of the processing solution over the entire surface of the film.

It is another important object of the present invention to provide an improved photographic processing and in particular, developing apparatus which is compact so as to take up a minimum of space in the usually crowded quarters of the amateur, which is portable so as to be readily installed for use and removed for storage when not needed, and which is economic in price in order to be within reach of every amateur wishing to perfect his work without excessive additional expense.

It is a further object of the present invention to provide photographic equipment for home use which is particularly adapted for reversal processing and multiple exposure to take place in a continuous operation.

Another object of the invention is to provide photographic processing equipment with time and cost saving features accomplished by a motor drive rendering the operation automatic, and a configuration specifically designed to require a minimum of processing solution.

A further object of the present invention is to provide a motor driven rack for processing photographic film with adjustable speed characteristics to adapt the same to varying processing conditions and requirements.

A still further object of the present invention is to provide photographic film processing equipment capable of processing and, particularly, developing a complete standard length roll of film at one time, eliminating the need for splicing and further enhancing uniformity of processing.

Other objects of the invention and the manner in which the same are attained will become apparent as this specification proceeds.

The present invention contemplates to achieve the above objectives by providing a film processing rack comprising two reels. The diameters of these reels are sufficiently different to permit, in one position of the device, one reel to fit inside the other. One of the reels is mounted on a hollow shaft which may be operatively connected to a motor drive, and the other reel is mounted on a second shaft which is arranged for sliding

2

displacement within the first-named hollow shaft, a telescopic arrangement supporting the two reels alongside each other as well as one on top of the other. As will be more fully explained below, the device includes some means for locking and disengaging the two reels to and from one another, so that the two reels may be driven separately as well as jointly, other means for coupling the hollow shaft to the motor drive, a tilting mechanism for lifting the device from a tray without the need for removing the device from its support, as well as suitable mounting means for the new piece of photographic equipment of the invention.

10 In the drawings accompanying the present specification and forming part thereof, a preferred embodiment of the invention is illustrated diagrammatically, by way of example, but we wish it to be understood that we do not desire to be limited to the exact details of construction, design and mode of operation shown and described for purposes of illustration, as numerous variations and modifications within the scope of the appended claims may be made without departure from the spirit of the invention and without sacrifice of any of the advantages thereof.

15 In the drawings:

Fig. 1 is a blown up, perspective view, of one preferred embodiment of the apparatus of the present invention; and

20 Fig. 2 is a vertical section therethrough, with the reels in telescoped position and shown as immersed in a tank.

25 Referring now more specifically to the accompanying drawings, wherein like parts are indicated by identical reference numerals, a casing 10 is shown to contain therein a small electric motor 12 which may have conventional cord connection to the house current and be controlled by the dial switch 13.

30 The motor 12 may have the vertical shaft 14 carrying a bevel gear 15. A cooperating bevel gear 16 which engages the gear 15, is mounted on a sleeve 17 journalled in bearings 18 set in opposed walls of the casing 10. The sleeve 17 projects slightly from either side of the casing 10 and serves as a bearing for one end of a hollow shaft 19.

35 The end of shaft 19, which is arranged within the sleeve 17, is internally threaded to receive the correspondingly threaded clutch screw 20 inserted through the end of the sleeve 17 at one side of the casing 10. When the clutch screw 20 is turned, it bears against the contiguous projection of the sleeve 17 and draws the hollow

shaft 19 inwardly thereinto, so that the ring 21 fixed in suitable position on the shaft 19, at the opposed end of the casing 10, is frictionally engaged against the contiguous projecting edge of the sleeve 17, to rotate therewith when the sleeve 17 is rotated by the motor 12 and gears 15 and 16.

Fixed on the hollow shaft 19 is a reel 22, preferably formed of two end sprockets 23 having the radial fingers 24 and the bars 25 extending between the fingers 24. One or more of the bars 25 may be provided with spacer or guide pins 26, for the purpose of spacing or separating adjacent film windings. One of the bars 25 may be made radially adjustable on its supporting fingers 24 to take up slack on the film when moist, in a manner readily understood and not shown.

A second shaft 30 is arranged for sliding, telescope-type displacement within the hollow shaft 19 and to revolve freely within the shaft 19. This shaft 30 also mounts a second or outer reel 31 which comprises a sprocket 32 at one end, and a ring 33 at the other, inner end, so that the reel 31 may fit over the inner reel 22, with the bars 34 extending between the sprocket fingers 35 and the ring 33. One or more of the bars 34 may also be provided with film spacing pins 36 and one of the bars 34 may, likewise, be arranged for adjustable radial displacement, in a manner readily understood and not thought necessary to be shown, for the purpose of taking up any slack in the film that might result from the moistening of the film.

A lock pin 37 may be carried on the sprocket 32, adapted to engage a depression or aperture 38 in the corresponding sprocket 23 of the reel 19, to interlock the two reels for simultaneous rotation, when desired.

Means may be provided for supporting the forward or inner end of the reel 31 against vibration during rotation. One form of such means may comprise the sprocket 40 mounted on shaft 19, intermediate the reel 22 and the ring 21, in slidable relation thereto, whose fingers 41 may have shoulders 42 formed on their ends to frictionally engage thereon the ring 33 of the reel 31.

The casing 10 may be pivotally connected with the aid of a stop hinge 43 either to a supporting table or, as illustrated, to a supporting plate 44 which, by means of a bracket 45 and a screw 46, may be removably secured to a table top or the like.

A tray or trough 47 may be positioned adjacent the housing 10, to contain the developing liquid, or the like, so that the reels 22 and 31 may be partly immersed therein when in horizontal position.

In the operation of the apparatus according to the invention, the film to be processed is wound on the reels. The winding is begun on the inner reel 22, while the outer reel is in withdrawn position relative thereto and is stationary while the inner reel 22 is turned for the winding. When winding of the inner reel is completed, the outer reel 31 is telescoped thereover and interlocked therewith, the film continuation is brought out between two of its bars 34, and the winding is continued on the reel 31. When the winding operation is completed, the whole device is tilted upward until stopped by the hinge 43 to permit proper placement of the trough 47, whereupon the device is returned to its horizontal position, with the lower portions of the reel immersed in the liquid in the trough.

Operation of the motor results in a uniform

rotation of the reels and a uniform, homogeneous distribution of developing or other processing fluid along the entire surface of the film. When a second exposure is called for, the device 5 is tilted upward again, the tray is removed, the locking pin disengaged and the outer reel is returned to withdrawn position, so that the entire surface of the film may be exposed uniformly and homogeneously, without any need 10 for removing the film from the reels. When the second exposure is terminated, the procedure is reversed and further processing is continued in the simple, time saving manner described.

This completes the description of the embodiment 15 of the apparatus of the present invention illustrated in the drawings and of the methods of its operation. It will be readily apparent that many advantages are inherent in the film processing apparatus of the invention; the most significant of which are the compactness and space 20 saving characteristics, its time and labor saving aspects, all coupled with the uniform, homogeneous distribution of processing fluid over the entire surface of the film made possible by it.

We claim:

1. A device for supporting a roll of film during processing, comprising, in combination, a motor, a shaft driven by said motor, a reel axially mounted on the said shaft, a second shaft 25 supported on said first named shaft for displacement in axial direction relative thereto, and a second reel adapted to fit over said first reel axially mounted by one end on said second shaft in overhanging relation thereto, whereby said second reel may be disposed over said first reel and in one position and to one side of said first reel in another position.

2. A device for supporting a roll of film during processing, comprising a pair of telescoping 30 shafts, a reel axially mounted on each of said shafts, one of said reels being of greater diameter than the other of said reels and adapted to fit thereover, at least one of said reels supported by one end in overhanging position on its supporting shaft, whereby said reels may be nested one within the other in one position and axially displaced relative one another in another position, driving means operatively associated with one of said shafts, and means for interengaging said reels when in nested position to be thereby simultaneously driven by said driving means.

3. A device for supporting a roll of film during processing, comprising a pair of telescoping shafts, a motor operatively associated with the outer of said shafts, a reel axially and fixedly mounted on said outer shaft, a second reel of greater diameter than said first named reel axially mounted by one end on the inner of said shaft in overhanging position relative thereto; whereby said second reel may be nested over said first reel in one position and axially displaced to one side thereof in another position, and means for interlocking said second reel over and to said first reel whereby said reels may be simultaneously driven by said motor.

4. The device of claim 3 wherein said inner shaft is rotatably as well as axially slidably disposed in said outer shaft whereby said reels may be rotated independently of one another when not in interlocked position.

5. The device of claim 4 wherein clutch means are provided for engaging and disengaging said outer shaft with its operatively associated motor.

6. The device of claim 5 in which said shafts and said motor are tiltably mounted on a supporting structure.

7. The device of claim 3 associated with a supporting structure and means for tiltably supporting said shafts and said motor on said supporting structure.

ALBERT DEL POZO, JR.

MICHAEL W. METTENLEITER.
